(57) **CLAIM**

The ornamental design for a screwdriver handle, as shown and described.

DESCRIPTION

FIG. 1 is a perspective view of a screwdriver handle showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view illustrating an application of a screwdriver handle showing my design;

FIG. 9 is a perspective view illustrating another application of a screwdriver handle showing my design;

FIG. 10 is a perspective view illustrating the other application of a screwdriver handle showing my design; and,

FIG. 11 is a perspective view illustrating the other application of a screwdriver handle showing my design.

The broken line showing of the screwdriver handle is for illustrative purposes only and forms no part of the claimed design.
